RACK FOR CARTONS

George S. Snyder, New York, N.Y., assignor to The Coca-Cola Company, New York, N.Y., a corporation of Delaware

Application July 28, 1958, Serial No. 751,504

8 Claims. (Cl. 211—49)

This invention relates to display racks, more particularly of the type employed for displaying cartons of bottled goods, for example beverages and the like, in retail establishments. Racks of this general character are widely used in connection with the sale of soft drinks, more especially when packaged in cardboard containers such as an open-topped carton formed to provide a carrying handle and containing compartments for a plurality of bottles or other containers. Such cartons of bottled goods have frequently been stacked one upon another, without the use of racks of shelves of any character but, for the sake of neatness in appearance and avoidance of accidental breakage, it is desirable to employ a rack having sides and a back to maintain vertical alignment of the stacked cartons. Such racks have heretofore been provided with shelves upon which the cartons of bottled goods are placed and supported, a layer of cartons on each shelf. Such an arrangement possesses the disadvantage that access to the rearmost cartons on a shelf, after the forward cartons have been removed, is impeded by the presence of the next higher shelf. This disadvantage has been overcome, in the case of one such rack now in use, by hinging the shelves at the rear and employing springs for swinging each shelf upwardly after the last carton has been removed therefrom, thus exposing the cartons on the next lower shelf. The cost of such racks is, of course, somewhat greater than that of racks having fixed shelves.

The general object of the present invention is the provision of a rack of the general character described, but of a more simple and less expensive construction than those mentioned above. More specifically, it is an object of the invention to provide a rack comprising a base, sides, and back, and a plurality of limp, flexible dividers, as distinguished from shelves, each adapted to rest upon the tops of the beverage containers in the cartons immediately subjacent thereto, said dividers being slidably mounted in slots provided in the back portion of the rack and being weighted at their rearward edges, whereby each flexible divider will automatically slide rearwardly and downwardly as soon as it is unloaded, thereby exposing the cartons resting upon the next lower divider and the beverage containers therebeneath. Such dividers are provided with stop means at their rearward and forward edges for preventing their accidental withdrawal from the associated slot, either forwardly or rearwardly, and may also be provided with handle means at their forward edges to facilitate drawing the dividers forwardly through their associated slots when the rack is being loaded. The handle means may take various forms, several of which are described and illustrated herein.

Other and further objects, features and advantages will be apparent from the description which follows, read in connection with the accompanying drawings in which

Figure 1 is a transverse vertical section through this rack;

Figure 2 is a vertical transverse section on line 2—2 of Figure 1;

2

Figure 3 is a fragmentary horizontal section on line 3—3 of Figure 1;

Figure 4 is a fragmentary perspective view illustrating a single flexible divider member and its relationship to the associated slot; and

Figures 5, 6 and 7 illustrate, respectively, alternative forms of the divider illustrated in Figure 4.

In order to facilitate an understanding of the invention, reference is made to the embodiments thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

A rack constructed in accordance with the present invention may be fabricated of any suitable material and in any suitable style, the essence of the invention residing in the provision of the aforementioned vertically spaced, horizontally disposed slots in the back portion and the flexible dividers, weighted at their rear edges and slidably mounted in such slots. However, for reasons of ease and economy of manufacture, convenience in shipping, durability, etc., it is customary to fabricate display racks of the general character in question from steel rod stock, suitably bent and welded, and the present rack has been illustrated as so constructed.

The rack comprises generally a base portion 10, opposite side portions 11 and a back portion 13, suitably joined, as by welding, into an integral structure. The base 10 comprises a carton supporting platform 14, which may consist of a rectangular grillwork of suitable size, a rectangular framework 15 which rests upon the floor or other surface upon which the rack is located, and vertical members 16 and 17 spacing the platform 14 a suitable distance above the framework 15. The sides 11 and back 13 are also secured to the framework 15 and to each other, as by welding, and are formed of interconnected vertical and horizontal rod members, some of which may be curved as illustrated at 18 in Figure 1. The details of construction of the side members form no part of the present invention, and will not be further described.

The back 13 comprises vertical members 19 secured to the rearward edge of the framework 15 and joined at their upper ends by cross member 21, and, disposed rearwardly of members 19, vertical members 22 secured to the respective rearward corners of the platform 14 and connected at their upper ends by cross member 23. The member 23 is also welded to the vertical members 19, and similar cross members 24, 25, 26 and 27 extend between, and are connected to, vertical members 19, at vertically spaced intervals, the cross members 23—27 being disposed between vertical members 19 and 22 in each instance, and connected to the latter as well as to members 19.

Another series of cross members 28, 29, 30, 31 and 32 extend horizontally between, and are welded to, the forward surfaces of vertical members 19, the cross members 28—32 being disposed slightly below the respective cross members 23—27. Thus, the cross members 23 and 28 define upper and lower edges of a horizontal slot extending between vertical members 19, and similar slots are formed, at vertically spaced intervals, between cross members 24 and 29, cross members 25 and 30, cross members 26 and 31, and cross members 27 and 32. The back portion 13 is completed by the provision of vertical members 33, the respective ends of which are bent forwardly and welded to cross member 21 and to framework 15, respectively, the purpose of the members 33 being to space the entire rack

suitably outward from a wall or other vertical surface against which it may be located, to provide working room for the flexible dividers to be described. The members

33 may be two or more in number, four being illustrated in the present instance.

A flexible divider 34 is slidably mounted in each of the aforesaid horizontal slots formed by cross members 23, 28, etc., the dividers 34 being preferably formed of plastic material of sufficient stiffness to resist wrinkling or inadvertent creasing, but having no permanent set and being of sufficient flexibility to allow them readily to slide, by gravity, from the full line position of the lowermost divider 34 in Figure 1 to the dotted line position of same, flexing about the cross members 28-32, as the case may be, as they do so. Each divider 34 is provided with a weight at its rearward edge which weight, in the illustrated embodiment, comprises a metal rod 35 extending entirely across the divider 34 and projecting beyond the side edges thereof so as to engage against vertical members 22 when the divider is pulled forwardly, to prevent it from being withdrawn from its associated slot. The rod 35 may be secured to the divider 34 in any suitable fashion, as by being inserted and adhesively secured in a tubular hem 36. A similar rod 37 (Figure 4) of substantially less weight, is similarly secured to the forward edge of each divider 34 and serves both as a handle for drawing the divider forwardly, and as a stop means for preventing the divider from sliding out of its associated slot as it moves rearwardly, the rod 37 being adapted to engage vertical members 19 when the divider 34 moves rearwardly.

In the embodiment of Figure 5 the divider 34 is provided with an integral roll 38 of the same material, which serves as handle and stop member, being of a diameter which exceeds the vertical dimension of the associated slot. In Figure 6 the divider 34 is provided with a rigid upturned flange 39 serving the same purposes, and in Figure 7 with a rigid, upstanding handle 40 for like purposes.

As will be seen from Figure 1, the base portion 10 is of such vertical dimension that the spacing of the platform 14 from the floor, when added to the vertical dimension of the containers to be supported thereon, at least equals the fore and aft dimension of the lowermost divider 34. Thus, when the latter is in the retracted position illustrated in dotted lines, the rearward edge thereof will not reach the floor, and the divider, therefore, cannot interfere with convenient loading of the platform 14. In loading the rack, the platform 14 is completely loaded with a suitable number of cartons of beverage containers, after which the lowermost divider 34 is drawn forwardly and another layer of cartons is disposed thereon. The next higher divider 34 is then drawn forwardly and the operation repeated until the rack is completely loaded, the last layer of cartons being disposed upon the uppermost divider 34.

As each layer of cartons is removed, as by purchase, the removal of the last carton of such layer releases the underlying divider 34, which will then automatically slide rearwardly exposing the next subjacent layer of cartons. In this manner, each carton of each layer is made completely accessible to the prospective customer, and may be removed from the rack readily and without difficulty.

In this way, the inconvenience and loss of space involved in the use of fixed shelves are avoided, and the expense and possible malfunctioning of hinged shelves are also avoided.

Having thus described the invention, what is claimed as new and desired to be secured by Letters Patent is:

1. A display rack for articles comprising a horizontal base, vertical sides and a vertical back portion connecting the rearward edges of said sides, said sides and back portion being secured to and extending upwardly from said base, said base comprising a platform for supporting articles to be displayed, said back portion being formed to provide horizontal slots extending therethrough from side to side at spaced intervals above said platform, which intervals correspond to the vertical dimension of the articles to be displayed, and a limp, flexible divider member slidably mounted in each said slot for fore-and-aft movement therein, each said flexible divider member having stop means at its forward and rearward edges to prevent its withdrawal from said slot, and means weighting each said flexible divider at its rearward edge sufficiently to cause said divider automatically to slide rearwardly and downwardly to a position behind said back portion when unloaded.

2. A device according to claim 1, including means spacing said platform above a floor or other surface upon which said rack is positioned, the amount of such spacing, added to the distance above said platform of said lowermost slot, being not less than the fore-and-aft dimension of the divider mounted in said lowermost slot.

3. A device according to claim 1, including means secured to and projecting rearwardly from said back portion to space the latter from other objects by a distance not less than that occupied by said said dividers when the latter are in their unloaded position.

4. A device according to claim 1, said stop means and weighting means at the rearward edges of said dividers comprising elongated weights projecting laterally beyond the side edges of said slots.

5. A device according to claim 1, said stop means at the forward edges of said dividers comprising upturned members of a height exceeding the vertical dimension of said slots.

6. A device according to claim 1, said stop means at the forward edges of said dividers comprising members projecting laterally beyond the side edges of said slots.

7. A device according to claim 1, said stop means at the forward edges of said dividers serving also as handles for pulling said dividers forwardly.

8. A device according to claim 1, said dividers comprising limp, flexible sheets of extruded plastic material of sufficient stiffness to resist wrinkling.
